AUTOMATIC LOCKING DRUM FILE

Frank D. Jonas, East Williston, N. Y., assignor to
Oxford Filing Supply Co. Inc., Brooklyn, N. Y.,
a corporation of New Jersey

Application March 1, 1944, Serial No. 524,552

8 Claims. (Cl. 129—16)

1

This invention is concerned with improvements in filing devices particularly for use in filing cards, comprising the drum or wheel type of device having a series of trays to receive the cards in combination with automatic locking devices whereby the cards are locked in the trays except when the drum or wheel is in position for working with the cards of one tray, at which time they are released for removal.

The main objects of the invention are to provide a simple structure mechanically providing card receiving trays or compartments within which a large number of cards in proportion to the size of the device may be stored; providing automatically operating locking devices which lock the cards in the trays in all positions thereof with the exception of the tray exposed for use; providing means for locking the cards of the exposed tray in place against unauthorized removal of the cards; and providing automatic indexing means to aid in centering the exposed tray in working position.

Other and more detailed objects of the invention will be apparent from the following disclosure when taken in connection with the drawings, in which several embodiments of the invention are illustrated.

This invention resides substantially in the combination, construction, arrangement and relative location of parts as will be described in detail below.

In the accompanying drawings,

Figure 1 is a side elevational view of a structure in accordance with the principles of this invention with some portions of the housing broken away and some parts omitted for the sake of simplicity;

Figure 2 is a left hand elevational view thereof with a portion of the end wall broken away;

Figure 3 is a detailed cross-sectional view showing the locking mechanism;

Figure 4 is a face elevational view thereof;

Figure 5 is a view diagrammatic in form, illustrating more clearly one form of card locking device;

Figures 6, 7, 8 and 9 are similar views of four modified forms of locking devices.

In the card filing art it is not new to assemble filing cards on some form of rotatable drum or wheel type of carrier. In this type of device it is usual to mount the cards on the drum or wheel with their planes parallel to the axis of rotation of the drum or wheel, and to provide some form of device for locking the cards thereon. With arrangements of this type, the cards are so locked on the wheel by engagement of a mounting ring

2

incorporated therein with a slotted hole in the bottom edge of the card. To remove or insert cards in such a device they must be either handled individually by forcing them off of or onto the ring, or the ring itself must be in segmental form so that the segments with the attached cards can be removed from the wheel and the cards separated therefrom by sliding them off an end of the segment. In the case of removable ring segments 5 some form of manual release and securing means must be provided to permit of the removal and replacement of the individual segments with attached card batches. Furthermore, in such arrangements the cards do not rest uniformly 10 on the peripheral surface of the wheel and hence their top edges at the outer circumference do not present a uniform surface for fingering. It is, therefore, difficult, if not impossible, to separate individual cards for access merely by fingertip 15 action, such as may be accomplished with accurately sized cards when they are arranged on a flat supporting surface as in the device herein disclosed which has none of these disadvantages.

A very important feature of this invention resides in the arrangement whereby the planes of the cards extend at right angles to the axis of rotation of the support as distinguished from the structures described above where the cards lie in the planes of the radii of the support. In the 20 file of this invention the cards stand up uniformly resting as they do on a plane surface and do not, as in the other device, flop over in batches and turn and skew within the limits allowed by their mounting as the wheel is slowly turned to bring the cards into position for exposure. In the prior device, the cards being on a circular surface so to speak, present a very irregular fingering surface as distinguished from the device of this invention where the cards resting on a 25 plane surface provide a very uniform fingering surface. Indeed the differences are so great that in the prior art devices precision rotary cut cards are of no importance because they cannot be fingered to separate them but must be thumbed at 30 the corners just like the pages of a book in order to separate them. In the device of this invention, the cards resting on a plane surface present a very uniform fingering surface and, therefore, precision rotary cut cards can and desirably are used. In the prior art arrangements the cards must be snapped off of and onto the ring when 35 removing and replacing them and as a result the card stock must be of very high quality in order that the ears of the slotted mounting holes can 40 withstand such abuse. With the device herein 45 50 55

disclosed, all the freedom and regularity of arrangement present in a regular card tray is available. The cards can be separated by light finger on the top edge if they are, as they can be in this case, rotary cut since the top surface conforms to the plane surface of the compartment floor in which they are mounted. There is no twisting or skewing of the cards because the supporting surface is flat and does not encourage it as it does in the other type of wheel. Furthermore, one or a batch of cards may be removed unimpeded by the necessity of snapping onto and off of a mounting ring. They come out of and into the file compartment just as easily as they do in a plain file drawer or box.

In the prior art devices the usual arrangement involves a continuous, although slow movement of the wheel while in use, whereas in the device herein disclosed the wheel is stationary while the cards are being examined. Thus there is less eye-strain on the part of the operator since it requires less effort for the eye to travel along the guides when they are stationary than it does when the guides move past the eye.

In accordance with this invention the device is provided with card receiving trays or receptacles, a type of storage container more common in the card filing art, built into a drum or wheel so that when the cards are mounted therein they lie in planes at right angles to the axis of rotation of the drum or wheel and rest upon a plane surface. Thus, for example as illustrated in Figures 1 and 2, the file structure includes a pair of suitably shaped and proportioned end plates 10 having peripheral flanges 11 to house the operating structure connected to the ends of an axially extending reinforcing housing or base 12 to provide a self-sustaining rigid structure. Extending between the end walls 10 is a shaft 13 which likewise interconnects the end walls to contribute to their rigidity. Rotatably mounted on the shaft 13 is a drum or wheel including a pair of end plates 14 in the form of a cross having arms of equal length, as clearly illustrated in Figure 2. Extending between opposed pairs of arms which are circumferentially aligned, are the card trays comprising the side walls 15 and the bottom wall 16. In the form of the device illustrated there are four of these trays, but it is of course apparent that the structure could be modified in the larger sizes to provide space for more than four trays. In the structure shown the right angle spaces lying between adjacent pairs of trays are closed off by transversely curved filler posts 17 which serve to impart to the drum a substantially cylindrical cross-sectional form. All of these parts, which are preferably made of metal, are secured together in any suitable manner as by welding and the like, and the specific details of construction thereof can be varied and amplified as conditions suggest.

Each of the trays is provided with a central slot 18 extending throughout the length of the bottom wall into which project the locking vanes 20 which, as illustrated, are in the form of radial extensions of the tubular members 19. These tubular members are journaled at their ends in the respective trays by means of stub shafts inserted in the ends thereof. At the left hand end, Figure 1, each stub shaft is provided, as shown, with a spur gear 22 of the same size and meshing with each other. Structurally these spur gears may be integral with or mounted on short stub shafts, as illustrated in Figure 1, which fit snugly in the ends of the tubular members 19, and are

secured thereinto in any suitable manner. One of each pair of these stub shafts at the gear ends as illustrated at 23, extends beyond the associated gear 22 and is connected by a lever 24 intermediate its ends, as is clear from Figures 1 and 2. One end of the lever 24 is connected by a tension spring 25 to a pin 26 mounted on the outer face of the end plate 14. As is clear from Figure 2, one of these levers is provided for each pair of locking vanes, that is one for each tray.

These elements are all mounted beside the end plate 14, see Figure 1, so that the cam rollers 27 mounted on the ends of the levers 24 may cooperate with a fixed cam 28 secured on the inner face of the adjacent housing wall 10 in any suitable manner, as by means of the rivets as indicated at 40 in Figure 4. The cam 28 throughout the major portion of its circumference is of cylindrical form but the portion which cooperates with the roller 27 of the tray exposed for use is of reduced radial length so that the vanes 20 are moved to a vertical position as shown in Figure 2. The other rollers 27 are on the cylindrical portion of the cam, and thus the vanes have been modified to a divergent locking position as clearly shown for the other trays.

At the other end of the device, that is the right hand end, Figure 1 is an indexing device comprising a cam 29 secured to the adjacent end wall 14. This cam for a four tray device has four seats relatively arranged so that a cam roller 30 rests in one of the seats when the structure is in a position so that a tray is exposed for use. The cam roller 30 is mounted on a lever 31 which is pivotally mounted at 32 on the adjacent housing end wall 10. A spring 33 is anchored on the main shaft 13 at one end and at the other end on a pin forming extension of the pivotal support for the roller 30. In other words, the tension spring 33 holds the roller 30 firmly against the periphery of the indexing cam 29.

Referring to Figure 5 it will be seen that the card C, indicated by a broken line, is provided with a triangular shaped notch N at its bottom edge at the transverse center, so that when the card is inserted in the tray the vanes 20 project into this notch. When the drum is rotated from the position shown in Figure 2 in a clockwise direction, for example, as the roller 27 moves up onto the cylindrical portion of cam 28, lever 24 is rotated causing the gears 22 to turn so that the vanes move apart into a divergent relation as clearly shown in Figure 2. In this position the vanes 20 lie parallel to the inclined space of the notch N and lock the cards C in the tray. They are thus locked in any one tray in all positions of the drum except the substantially vertical position of the uppermost tray of Figure 2, at which time they are unlocked so that they can be removed or new cards mounted in place. As soon as the drum is again rotated, and before it moves sufficiently so that the cards can fall out, they are automatically locked in place. The operation of the indexing mechanism is obvious. It merely serves as a convenient method of properly positioning the trays as they are exposed for use.

With this arrangement as described it is obvious that the cards in the uppermost tray are unlocked and so the mechanism of Figures 3 and 4 is provided to make it possible to lock the cards in this tray against unauthorized removal. To accomplish this the fixed cam 28 has its face adjacent the wall 10 cut away to form the recess 28' in which a segmental shaped plate 38 lies. This

plate is freely rotatable on the shaft 13 and is of an angular width sufficient to bridge the dwell portion of the cam. This segmental plate is shown in inactive position in the figures, but may be swung from the position shown to a position where it is aligned with the dwell of the cam. The radial dimensions of the segmental plate 38 are such that when it is aligned with the dwell of the cam it in effect forms a continuation of the cylindrical portion of the cam so that the arm 24 of the exposed tray is moved from the position shown in Figure 2 to a position corresponding to that of the other arms. In this position, of course, the vanes of the exposed tray are in locking position. As illustrated in Figure 4, means is provided for locking the segmental plate 38 in either its operative or inoperative position. Attached to the outer face of the end wall 10 is a hasp or ring 35 positioned at one end of an arcuate slot 34 in that wall. Near the other end of the slot is a similar hasp 36. Attached to the segmental disc is a hasp 37 which may move with it. When the disc is in the position shown hasp 37 is aligned with hasp 36 and the parts may be locked in this position by means of the padlock 39. On the other hand, when the segmental disc 38 is swung counterclockwise, Figure 4, into alignment with the dwell of the cam the padlock interconnects hasp 35 with hasp 37, and thus all the cards are locked against removal.

Some modified forms of locking devices are illustrated in the remaining figures. Thus in Figure 6 the card C is provided with a substantially circular notch N' extending as shown to the edge of the card. Journaled in the tray is a shaft 41 having a transversely extending vane 42 which projects radially from each side thereof. The key thus formed is properly dimensioned with the size of the notch so that it can rotate in the similarly shaped channel thus formed when a plurality of cards are aligned. Secured to the shaft is an arm 43 on which the cam roller 27 is mounted for cooperation with a fixed cam similar to that previously described. The key is illustrated in unlocked position so that the cards can be mounted and removed. However, when shaft 41 is rotated in either direction to a position so that the key or vanes 42 are horizontal, it will be apparent that the cards are locked in place.

In the modification of Figure 7 the bottom wall of the tray which has a longitudinal slot in the bottom thereof similar to that of Figure 1, has an upturned flange 16' extending at right angles to the bottom of the tray. A shaft 41 similar to that of Figure 6 is journaled below the tray and has a single positioning arm 42' extending throughout the length of the tray and terminating in a hooked end. As before the lever 43 is connected to the shaft 41 and is provided with the cam roller 27. In this arrangement the cards have rectangular notches N'' near their bottom edges which extend to the edge as shown, so that when the vane 42' is in the position shown the cards can be removed, but when it is moved in counterclockwise direction to its locking position its hooked end will engage the notches and prevent removal of the cards.

In the arrangement of Figure 8 a pair of shafts 41 are provided to which are secured the plates 44 which extend vertically along the sides of the tray 15 to a point above them and just above the top edges of the cards C. The upper ends of the plates are bent over the cards and when these plates are in the position shown in the figure the cards are

locked against removal. When the tray is exposed for use, however, the plates 44 will move outwardly on the axes of the shafts 41 so that the cards can be removed. This arrangement differs from those previously described in that plain unnotched cards may be used.

Figure 9 illustrates sufficient of a further modification which is a variant of the structure of Figure 8 to make clear the intended structure.

10 In this case the cards C are provided with notches N''' at the side edges near the top and the plates 44 are of less width so that their bent ends can cooperate with the notches to lock the cards in place.

15 In the arrangements of Figures 6 to 9 inclusive it is apparent that the locking devices or keys can be operated in a manner quite similar to that illustrated for the structure of Figures 1 to 5 inclusive, or the operating mechanisms can be varied in a number of different ways.

20 I do not, therefore, desire to be strictly limited to the illustrative embodiments of my invention as disclosed herein but rather by the scope of the claims granted me.

25 What is claimed is:

1. A filing device comprising a fixed support, a filing card support rotatably mounted on said fixed support and providing a plurality of card trays, a plurality of cards in said trays, and locking devices cooperating with the cards to lock them in the trays including a fixed cam and means cooperating therewith upon rotation of said card tray support for moving the locking devices from and to locking position.

30 2. In the combination of claim 1, said locking devices including notches in said cards and cooperating keys movable to and from locking position.

35 3. A filing device comprising a fixed support, a rotatable filing card support mounted on said fixed support and providing a plurality of card trays, a plurality of cards in said trays, locking devices cooperating with the cards to lock them in the trays, and means for releasing the locking devices as the respective trays are moved to work position by rotation of said card tray support, said locking devices including notches in said cards and cooperating keys movable to and from locking position in said notches.

40 4. In the combination of claim 3, each of said trays having a longitudinal slot in its bottom wall and said keys projecting through said slots and into the notches of the cards.

45 5. In the combination of claim 1, means for preventing cooperation of said means for moving the locking devices.

60 6. In a card filing device of the type described, the combination including a rotatable drum providing a plurality of card supporting trays, a plurality of cards in said trays, means for locking the cards in said trays, means for automatically and successively releasing them as each tray moves into exposed position, and means for holding the locking means of the exposed tray in locking position when desired, said releasing means including a fixed cam and cooperating lock operating devices for each tray mounted on the drum for rotation therewith.

65 7. In the combination of claim 6, said cards being notched and said locking means comprising a rotatable member having a key movable into and out of locking relationship with the notches in the cards.

70 8. In a card filing device of the type described, the combination including a rotatable drum pro-

viding a plurality of card trays, a plurality of notched cards in said trays, means for locking the cards in said trays, means for automatically and successively releasing them as each tray moves into exposed position, and said locking means comprising a pair of vanes movable into and out of locking relationship with respect to the notches in said cards.
